(57) **CLAIM**

The ornamental design for a conferencing device, as shown and described.

DESCRIPTION

FIG. 1 is a top, front, right-side perspective view of a conferencing device;

FIG. 2 is a bottom, back, left-side perspective view thereof;

FIG. 3 is a front view thereof;

FIG. 4 is a back view thereof;

FIG. 5 is a right-side view thereof;

FIG. 6 is a left-side view thereof;

FIG. 7 is a top view thereof;

FIG. 8 is a bottom view thereof;

FIG. 9 is second front view including disclaimed environment of the conferencing device;

FIG. 10 is a second back view thereof;

FIG. 11 is a second left-side view thereof; and,

FIG. 12 is a second bottom view thereof.

The dashed broken lines depict portions of the conferencing device or environment of the conferencing device that form no part of the claimed design.
